EXPLOSIVELY ACTUATED PRESS

Robert Temple, Jr., Pittsburgh, Pa.

Application May 22, 1936, Serial No. 81,288

17 Claims. (Cl. 140—113)

This invention relates to presses and more particularly to apparatus for compressing metal sleeves on wires or cables as, for example, to connect them electrically.

5 The present invention comprises an improvement upon my Patent No. 2,030,803 relating to a compressing device and disclosing and claiming broadly the principle of a portable press of the character specified wherein the power for applying pressure is obtained by the expansive action 10 of an explosive charge. While the construction and operation taught by my referred-to patent are entirely satisfactory for most purposes, I have found it advantageous to provide means for holding and centering the work during the compressing operation. Likewise it has now been determined that in certain uses where the press is employed to perform a number of compressing actions along the same member as, for example, required 15 in the joining of heavy cables by relatively long sleeves, an improved appearance of the finished joint can be obtained by moving both die members toward each other simultaneously. In this manner any offsetting tendency longitudinally 20 of the sleeve is largely eliminated and moreover the holding of the sleeve and cables prior to joining is facilitated. Likewise with a single moving piston and die member there is a tendency to transmit the impact of the starting and 25 stopping of the die to the frame which is undesirable particularly where centering of the material worked on is important.

It is accordingly the general object of my invention to provide a press having a plurality of work-engaging members adapted to receive the work therebetween, which members are simultaneously moved toward each other by the expansive action of one or more explosive charges.

Another object of my invention is the provision 30 of improved means for positioning the work relative to the work-engaging members.

A further object of my invention is to provide means for maintaining the work-engaging members in fixed position until substantially a maximum 35 pressure is obtained from the explosive charge tending to move the members together.

Another object of my invention is to provide a press of the character described wherein the features of portability, strength and lightness, 40 featuring the compressing apparatus of my above referred-to patent are retained while doing double the work with no impact shock transmitted to the frame since the operation of the dies counterbalance.

45 The foregoing and other objects of the in-

vention are achieved by the provision of a press comprising a frame having a plurality of work-engaging members mounted therein for movement to and from each other and shaped to receive a piece of work therebetween. The frame 5 also carries means adapted to receive an explosive charge with other means for exploding the charge. Associated in the combination are means actuated by the charge explosion intending to move the members toward each other 10 simultaneously under high pressure with mechanism preventing the movement of the members until substantially a maximum pressure is obtained from the explosion.

In the accompanying drawings, Fig. 1 is a side elevation partly in section of one embodiment of my invention; Fig. 2 is a plan view partly in section and taken on line II—II of Fig. 1; Fig. 3 is a vertical transverse cross-sectional view taken on line III—III of Fig. 1; Fig. 4 is a vertical transverse sectional view taken on line IV—IV of Fig. 1 but with the die members shown in compressing position; Fig. 5 is a fragmentary longitudinal cross-section view taken on line V—V of Fig. 4; Fig. 6 is an end elevation of the 25 frame proper; Fig. 7 is a cross-sectional view of a typical product of the press and more specifically comprises a sleeve joining cable ends together; Fig. 8 is a plan view of another embodiment of my invention; Fig. 9 is a vertical longitudinal sectional view of the apparatus of Fig. 8 as taken on line IX—IX thereof; Fig. 10 is a transverse vertical cross-sectional view taken on line X—X of Fig. 9.

Although the apparatus of my invention is 35 broadly applicable to substantially any pressing operation involving the use of work-engaging, forming or die members, it particularly adapts itself to securing pipes, tubes, electrical or other cables together with metal sleeves and accordingly, in the several forms of the invention herein considered, use of the invention to connect electric cables has been illustrated and described.

More particularly, referring to Figs. 1 to 6, the numeral 10 indicates a base or frame formed 45 with aligned spaced block portions 12 and 14. Each block portion is formed with a bore receiving sleeves 16 and 18 respectively which are preferably made of stainless steel or other corrosion resisting metal. The sleeves 16 and 18 are held 50 tightly in position as, for example, by providing abutments 20 and 22 at the adjacent ends of the bores and forcing the sleeves against the abutments by means of plugs 24 and 26 respectively, each having a threaded periphery received in a 55

suitable tapped opening in the block portions. Preferably copper or brass sealing washers 28 and 30 are provided between the ends of the plugs and the sleeves for positively sealing both in position.

The sleeves 16 and 18 form cylinders slidably receiving respectively piston hammers 32 and 34 formed with substantially square heads 36 and 38. Each of the piston heads 36 and 38 is provided with a central recess receiving circular bosses 40 and 42 formed integral with work-engaging die members 44 and 46. The bosses 40 and 42, and thus the die members, are removably connected with the piston hammers 32 and 34 respectively through the use of screws 48 and 49.

Associated with the die members 44 and 46 are means for positioning the work which in the embodiment of the invention illustrated comprises a metal sleeve S adapted to connect cables C and C'. The positioning means includes a jig box 52 having a flat bottom, vertically extending side walls and open ends so that, as seen in the several figures of the drawings, the jig box surrounds the die members 44 and 46 and allows for sliding movement thereof in the box. The vertical side walls of the jig box 52 are formed with opposed key-hole slots 58 which at their narrow portion are substantially equal to the diameter of the cables C and C', and at their circular portion are substantially of the same diameter as the sleeve S before it is compressed by the die members. Thus, by means of the key-hole slots 58 the sleeve S and cables C and C' are accurately positioned relative to the die members 44 and 46, as hereinafter more fully explained.

The jig box 52 is secured to and centered on the frame 10 by what I call a safety shear pin 60. Likewise, the die members 44 and 46 are secured to the vertical side walls of the jig box 52 by shear pins 62 and 64. It will be recognized that by the provision of the shear pins 60, 62 and 64 the die members 44 and 46 are positioned and held at equally spaced distances from the sleeve S and cables C and C'. It should be noted, however, that the jig box 52 is shorter than the distance between the block portions 12 and 14 by a distance somewhat greater than the combined movement of the die members 44 and 46 together during the compressing operation. This feature is clearly illustrated in Fig. 1 of the drawings and permits movement of the jig box relative to the frame 10 in case the safety shear pin 60 is sheared, as will be described in greater detail.

The plugs 24 and 26 are provided with central bores adapted to receive explosive charges which are preferably in the form of cartridges 68 and 70. It will be seen that for the proper operation of the mechanism described, the cartridges 68 and 70 must be simultaneously fired. In the embodiment of the invention shown this is achieved by the provision of a yoke indicated generally by the numeral 75, and having end portions 76 and 78 extending over the ends of the block portions 12 and 14 of the frame and received in apertures 80 and 82 formed in the frame. Preferably, as shown in Fig. 3, the yoke member 75 is received between vertically extending flanges 84 formed on the block portions 12 and 14 and while not illustrated in the drawings I contemplate the use of two or more spring-pressed ball detents for releasably holding the yoke on the frame.

Secured to the central upper portion of the yoke 75 is a nipple 86 having a bore receiving a cartridge 88 and adapted to be fired by a pin 90 slid-

ably mounted in a cap 92 having a removable threaded connection with the nipple 86. The firing pin 90 is provided with a slot at one side which receives the end of a screw 94 carried in the cap 92 whereby the firing pin is retained in the cap 92 but is capable of having sufficient movement to explode the cartridge 88 when the firing pin is struck from above as by a hammer.

The vertically upper side of the yoke 75 is formed with grooves which receive tubes 96 and 98, each slidably carrying closely fitting tappet rods 100 and 102 which move as pistons in the tubes. The tubes 96 and 98 have a forced gas-tight fit with the nipple 86 and are retained in the grooves in the yoke 75 by a cover plate 104 secured to the yoke. Mounted pivotally at each end of the yoke as by pins 106 and 108 are fingers 110 and 112 which are normally urged into contact with the ends of the tappet rods 100 and 102 respectively by compression springs 113 and 114. Firing pins 116 and 118 are mounted in the end portions 76 and 78 of the yoke in alignment with the cartridges 68 and 70 and are, respectively, normally urged outwardly into contact with the ends of the fingers 110 and 112 by compression springs 120 and 121.

It is believed that the operation of the apparatus will be apparent from the foregoing description. However, briefly summarizing, in the use of the mechanism the cable ends C and C' are inserted into the sleeve S which has been positioned in the round portions of the key-hole openings 58 in the jig box 52, as illustrated in Figs. 1 and 2. With parts in the positions shown in these same figures the firing pin 90 is struck with a hammer to explode cartridge 88. The expansive force of the exploded cartridge causes tappet rods 100 and 102 to move simultaneously as pistons in tubes 96 and 98 to rapidly tilt fingers 110 and 112, thereby driving firing pins 116 and 118 into cartridges 68 and 70 to simultaneously explode them.

The force of the explosions is transferred to piston hammers 32 and 34 but movement of the pistons and associated die members 44 and 46 is prevented by shear pins 62 and 64 until substantially a maximum pressure has been built up by the explosions. The particular pressure necessary to shear the pins 62 and 64 is, of course, dependent upon their size. In all events once the pressures from the explosions have reached a predetermined point, the pins 62 and 64 shear and the die members 44 and 46 are driven together with high velocity and power to effect a hammer-like compressing and die-shaping action upon the portion of the sleeve S positioned between the die members. In this manner the end of the cable C is very firmly secured to the sleeve S.

Yoke member 75 which merely fits down over the frame 10 is now picked off and new cartridges 60 are substituted for the fired cartridges 68 and 70. The cap 92 is unscrewed from the nipple 86 and a new cartridge is substituted for the fired cartridge 88. The die members 44 and 46 are moved apart and new shear pins are substituted for the sheared shear pins 62 and 64. The sleeve S is moved laterally through the jig box 52 to position it for the second compressing operation, namely, to secure the sleeve S to the cable C'. The mechanism is then actuated as before described to complete the joining of the cables together. The joined cables are removed from the apparatus by first removing the yoke 75 and then laterally moving the sleeve S out of the jig box 52, at which time the connected cables can be lifted out of 75

the apparatus since the cables are smaller in diameter than the slotted portion of the key-holes 58 on the sides of the jig box 52.

The purpose of the safety shear pin 60 is three-fold. First, it normally positions the jig box 52 relative to the die members 44 and 46. Second, it acts as a safety feature in case one or the other of the cartridges 68 and 70 fails to fire. If, for example, cartridge 70 fails to fire and cartridge 68 does fire, the pin 62 first shears and allows the die member 44 to drive down against the sleeve S. Since, however, the sleeve S is only supported by the jig box 52 the hammer-like blow of the die member 44 shears the safety shear pin 60 and drives the sleeve in the jig box down to a position where the sleeve is compressed between the then stationary die member 46 and the die member 44. This action is possible due to making the jig box 52 shorter than the distance between the block portions 12 and 14 of the frame by a distance slightly greater than the combined movement of the die members.

In addition to the foregoing, the safety shear pin 60 performs the function of synchronizing the compressive action of the die members 44 and 46. If, for example, one of the cartridges 68 or 70 is slower burning than the other or if the shear pins 62 and 64 do not yield at exactly the same time, the safety shear pin 60 functions to co-ordinate the compressing action of the die members. More particularly, if the cartridge 68 is a fraction of a second slower burning than the cartridge 70, the shear pin 64 yields a fraction of a second before pin 62 and the die member 46 is driven toward the sleeve S a fraction of a second before the die member 44. However, as will be seen from the drawings, the safety shear pin 60 is somewhat stronger than the shear pin 64 or 62 so that the fraction of a second needed to shear the pin 60 causes the die members 44 and 46 to do their work on the sleeve while it and the jig box 52 are still in a central position which is desirable as discussed above.

While the form of the invention illustrated in Figs. 1 to 6 and above described employs two cartridges for moving the die members simultaneously with a third cartridge being employed to simultaneously fire the die-moving cartridges, I likewise contemplate employing a single cartridge to simultaneously actuate both die members. Thus, in the embodiment of my invention illustrated in Figs. 8 to 10, the numeral 140 indicates a base-plate having a longitudinally extending groove 142 in its upper surface receiving a jig box 144 normally held against movement in the groove by a safety shear pin 146. Removably mounted on the base-plate 140 is a yoke frame 148 having spaced aligned bores receiving sleeves 150 and 152 preferably of stainless steel or other corrosion-resisting metal, and having a force fit in the bores. Slidably positioned in the sleeves are piston hammers 154 and 156 which are removably secured to die members 158 and 160, respectively. The die members are substantially rectangular in transverse cross-section and have a sliding fit in the jig box 144.

The yoke frame 148 is formed with a nipple 162 which is bored to receive a cartridge 164. To facilitate removal of the cartridge a metal bushing 166 adapted to receive the cartridge and, in turn, be received in the nipple 162 may be provided. The bushing 166 and cartridge 164 are removably held in position by a cap 168 having a threaded fit on the nipple 162, as illustrated in Fig. 9 of the drawings. Cap 168 carries a firing

pin 170 with a lock pin 172 holding the firing pin 170 in the cap but permitting limited movement of the pin sufficient to detonate the cartridge 164. Due to the difficulty of sealing the bushing 166 with respect to the nipple 162 during the discharge of the cartridge, I have found it advisable to extend the cartridge through the bushing into the bore of the nipple a sufficient distance so that when the cartridge is fired the brass of the shell is forced into sealing relation with the walls of the nipple 162.

The yoke frame 148 is provided with passage-ways 176 and 178 extending from the cartridge bore and the nipple 162 to behind the pistons 154 and 156, respectively. Removable threaded plugs 180 and 182 tapped into the yoke frame 148 and having conical inner ends facilitate the provision of the opposed bores for receiving the cylinder sleeves 150 and 152 and likewise may function as shown to limit the outward movement of the pistons 154 and 156. The base-plate 140 is formed with suitable recesses to receive the lower ends of the yoke frame 148, as best illustrated in Fig. 9.

The jig box 144 is provided with opposed key-hole slots 186 of which the circular portions are of a size to closely receive and support an eyelet E to be secured to the end of a wire W. The slotted portion of the key-hole slots 186 is of a dimension to allow the wire W to slip therethrough. As in the first-described embodiment of my invention, the die members 158 and 160 are secured to the jig box 144 by shear pins 188 and 190, respectively, and the jig box is made of a length less than the distance between the opposed ends of the yoke frame by an amount slightly greater than the total movement of the die members 158 and 160.

The operation of this embodiment of my invention is substantially identical with that heretofore described with the exception that, once the mechanism has been set up, the die members are actuated to deliver a hammer-like compressing and shaping blow upon the eyelet E by the expansive force exerted by the explosion of the single cartridge 164 which is detonated by striking the firing pin 170 with a hammer. The action of shear pins 188 and 190 and safety shear pin 146 is identical with that heretofore described in conjunction with the first embodiment of my invention. The reloading of the embodiment of my invention shown in Figs. 8 to 10 is somewhat more rapid than the three-cartridge type since cap 168 need only be removed and a new bushing and cartridge substituted for fired cartridge 164 and its supporting bushing 166. The die members 158 and 160 are pried apart and a new eyelet and wire positioned in the jig box, new shear pins 188 and 190 provided, and the cap is replaced, whereupon the operation can be repeated.

It should be understood that in the second embodiment of my invention cables can be connected by sleeves or other pressing or crimping operations can be performed as desired. However, ordinarily I contemplate pressing heavier members on the first form of my invention illustrated and described since the force exerted by the die members is the result of the explosion of two cartridges, one of which is positioned directly behind each die member. Of course, the second embodiment of my invention shown and described ordinarily employs a larger cartridge since it must actuate both pistons. However, in the usual practice of my invention the second embodiment thereof is employed on lighter work or upon

work requiring less pressure to achieve the desired result.

In the use of either embodiment of the invention disclosed I contemplate replacing the die members 44 and 46 or 158 and 160 with dies of different or related sizes so that the press can be readily adapted by a simple operation to handle a wide variety of sleeve, eyelet and cable sizes. Furthermore, the principles of my invention are applicable broadly to other operations than connecting sleeves and cables and work-engaging, forming, or die members adapted to perform various processes, such as the joining of pipes, may be used instead of the die members indicated.

From the foregoing it will be evident that the objects of my invention have been achieved by provision of relatively light weight, portable apparatus by sturdy and long-wearing character

adapted to be handled by the relatively unskilled operator and operating to perform rapidly a wide variety of pressing and die-forming processes and particularly adapted to secure cables together or metal eyelets thereto. The combination of the oppositely acting pistons and work-engaging members results in a press particularly free from shock and impact and the frame is without kick or jar which facilitates its support and the support of the work between the members.

Although in accordance with the Patent Statutes, two embodiments of my invention have been illustrated and described in detail, it should be understood that the invention is not limited thereto or thereby but is defined in the appended 35 claims.

I claim:

1. In combination, a frame having a pair of spaced apart but aligned cylindrical bores therein, a piston movably mounted in each bore, work-engaging means associated with each piston and facing each other so that upon movement of the piston toward each other any work positioned between the means will be acted on, explosive means associated with the pistons and adapted on firing to move the pistons simultaneously toward each other, means for actuating the explosive means, means for positioning the work between the work-engaging means, and means holding the pistons against movement until substantially the maximum explosive pressure has been reached.

2. In combination, a frame having a pair of spaced apart but aligned cylindrical bores therein, a piston movably mounted in each bore, work-engaging means associated with each piston and facing each other so that upon movement of the pistons toward each other any work positioned between the means will be acted on, explosive means associated with the pistons and adapted on firing to move the pistons simultaneously toward each other, means for actuating the explosive means, and means for positioning the work between the work-engaging means.

3. In combination, a frame having a plurality of spaced apart bores therein, a piston movably mounted in each bore, work-engaging means associated with each piston and facing each other so that upon movement of the pistons toward each other any work positioned between the means will be acted on, explosive means associated with the pistons and adapted on firing to simultaneously move the pistons toward each other, and means for actuating the explosive means.

4. In combination, a frame having a plurality of spaced apart bores therein, a piston movably

mounted in each bore, work-engaging means associated with each piston and facing each other so that upon movement of the pistons toward each other any work positioned between the means will be acted on, explosive means associated with the pistons and adapted on firing to move the pistons simultaneously toward each other, means for actuating the explosive means, and means holding the pistons against movement until substantially the maximum explosive pressure has been reached.

5. A press comprising a frame, a plurality of die members mounted in the frame for movement to and from each other and shaped to receive a piece of work therebetween, means in the frame to receive an explosive charge, means to explode the charge, means actuated by the charge explosion tending to move both die members toward each other under high pressure, means holding both die members against movement until substantially a maximum pressure is obtained from the explosion, and a jig for removably positioning the work between the die members.

6. A press comprising a frame, a pair of die members mounted in the frame for movement to and from each other, and shaped to receive a piece of work therebetween, means in the frame to receive an explosive charge, means to explode the charge, means actuated by the charge explosion tending to move both die members toward each other under high pressure, and means preventing the movement of both die members until substantially a maximum pressure is obtained from the explosion.

7. A press comprising a frame, a pair of die members mounted on the frame for movement to and from each other, and shaped to receive a piece of work therebetween, means in the frame to receive an explosive charge, means to explode the charge, and means actuated by the charge explosion tending to move both die members toward each other under high pressure.

8. In combination, a frame, dies slidably mounted in the frame for movement into and out of engagement, means associated with each die for receiving an explosive charge which charge when exploded is adapted to move the die, individual means for detonating each charge, and means including a centrally positioned holder for an explosive charge and a detonating mechanism for simultaneously actuating the individual detonating means.

9. In combination, a frame, dies slidably mounted in the frame for movement toward and from each other, means associated with each die for receiving an explosive charge which charge when exploded is adapted to move the die, and means for simultaneously detonating each charge.

10. In combination, a frame, dies slidably mounted in the frame for movement toward and from each other, means associated with each die for receiving an explosive charge which charge when exploded is adapted to move the die, individual means for detonating each charge, a jig box slidably mounted on the frame and adapted to releasably position the work between the dies, a safety shear pin normally fixing the position of the jig box on the frame and shear pins securing the dies in spaced relation to the jig box until a predetermined pressure is created by the explosion of the charges.

11. In combination, a frame, dies slidably mounted in the frame for movement toward and from each other, means associated with each die

- for receiving an explosive charge which charge when exploded is adapted to move the die, individual means for detonating each charge, a jig slidably mounted on the frame and adapted to 5 releasably position the work between the dies, and a safety shear pin normally fixing the position of the jig on the frame.
12. In combination, a frame, dies slidably mounted in the frame for movement toward and 10 from each other, means associated with each die for receiving an explosive charge which charge when exploded is adapted to move the die, individual means for detonating each charge, and a jig mounted on the frame and adapted to releasably position the work between the dies.
13. In combination, a frame, dies mounted in the frame for movement to and from each other, means positioned substantially equidistant between the dies and mounted on the frame for receiving an explosive charge, the frame having conduits connecting the back of the dies with the means receiving the explosive charge, means to fire the explosive charge, jig means mounted on the frame and positioning the material to be treated between the dies, and means on the jig means for holding the dies against movement toward each other until a predetermined pressure has been reached by the explosion of the charge.
- 20 14. In combination, a frame, dies mounted in the frame for movement to and from each other, means positioned between the dies and mounted on the frame for receiving an explosive charge, the frame having conduits connecting the back of 25
- the dies with the means receiving the explosive charge, means to fire the explosive charge and jig means mounted on the frame and positioning the material to be treated between the dies.
15. In combination, a frame, piston members mounted in the frame for movement to and from each other, means positioned equidistant between the piston members and mounted on the frame for receiving an explosive charge, and means actuated by the explosion of the charge to move 10 both piston members simultaneously toward each other.
16. In combination, a frame, a pair of work-engaging members movable to and from each other, a jig for supporting the work between the 15 members, means normally securing the jig to the frame but adapted to release when the forces on the jig exceed a predetermined amount so that the jig can move toward one or the other of the dies, and means securing the work-engaging 20 members to the jig in spaced apart relation but adapted to release when the forces on the members exceed predetermined amounts less than said first predetermined amount.
17. A hammer press comprising a frame, die 25 members slidably mounted in the frame for movement toward each other, means for simultaneously moving each die member toward the other with hammer-like force, and means centrally positioning the work between the die members, 30 said last named means being movable toward one or the other of the dies when a predetermined force thereon is exerted.

ROBERT TEMPLE, JR.
